United States Patent Office

Des. 212,587
Patented Nov. 5, 1968

212,587

BOTTLE

James A. Shepler, Toledo, Ohio, assignor to Owens-Illinois, Inc., Toledo, Ohio, a corporation of Ohio

Filed Oct. 18, 1967, Ser. No. 9,055

Term of patent 14 years

(Cl. D9—91)

FIG. 1

FIG. 2

FIG. 4

The sides opposite those seen in FIGS. 3 and 4 are the same in appearance as the respective sides shown.

The dominant features of my design reside in the portions shown in full lines.

I claim:

The ornamental design for a bottle, substantially as shown and described.
